DESIGN FOR A COLLAPSIBLE UTILITY CART
OR THE LIKE

Harry Stoll, New York, N. Y.

Application October 21, 1947, Serial No. 142,063

Term of patent 7 years

(Cl. D14—3)

To all whom it may concern:

Be it known that I, Harry Stoll, a citizen of the United States, residing at New York, in the county of New York and State of New York, have invented a new, original, and ornamental Design for a Collapsible Utility Cart or the like, of which the following is a specification, reference being had to the accompanying drawing, forming a part thereof.

In the drawing:

Fig. 1 is a front perspective view of a collapsible utility cart or the like, showing my design.

Fig. 2 is a vertical sectional view taken on the line 2—2 of Fig. 1;

Fig. 3 is a top plan view of Fig. 1; and

Fig. 4 is a perspective view of Fig. 1 showing the collapsible utility cart or the like in closed position.

I claim:

The ornamental design for a collapsible utility cart or the like, as shown.

HARRY STOLL.
